No. 12,850

April 4, 1882

UNITED STATES PATENT OFFICE.

HENRY PATTBERG, OF JERSEY CITY, NEW JERSEY.

DESIGN FOR A TOILET-CASE.

SPECIFICATION forming part of Design No. 12,850, dated April 4, 1882.

Application filed December 1, 1881. Term of patent 3½ years.

To all whom it may concern:

Be it known that I, HENRY PATTBERG, a citizen of the United States, residing at Jersey City, in the State of New Jersey, have invented and produced a new and original Design for Toilet-Cases, of which the following is a specification, reference being had to the accompanying drawings, forming part thereof.

Figure I is an outside view of my newly-designed case; Fig. II, an inside view of the same.

The leading feature of my design consists in the shape of the toilet-case, made to represent a photograph-album or book supported upon an easel, with an illuminated cover and suitable recess for the reception of a photographic picture. The case forms a box divided and opening in the center, the lower edge or end being made circular, similar to the back of a book, with the sides and top end recessed to represent the edges of the leaves or pages of a book, the front and back cover projecting

slightly above the sides and ends of the case. The front of the box has an opening, B, covered with glass, behind which a photographic or other picture may be placed. The cover of the case around the recess B for the picture is ornamented by a landscape, painted or printed thereon, consisting of a building or country church on one side and a tree on the other side of the recess B, with suitable foliage on top. Upon the four corners of the outside cover ornamental corner-pieces, similar to a well-bound book or album, are attached, and a clasp is attached at the upper end to hold and fasten the two parts of the box together.

I claim—

The design of a toilet-case, substantially as herein shown and described.

HENRY PATTBERG.

Witnesses:

HENRY E. ROEDER,
J. B. NONES.
